WITNESS:

26 17 John W. Wallace
INVENTOR
Victor G. Evans

UNITED STATES PATENT OFFICE.

JOHN WESLEY WALLACE, OF CARTIERSVILLE, QUEBEC, CANADA.

DOOR-LATCH.

1,360,835.

Specification of Letters Patent. Patented Nov. 30, 1920.

Application filed March 16, 1920. Serial No. 366,415.

To all whom it may concern:

Be it known that I, JOHN W. WALLACE, a subject of the King of Great Britain, residing at Cartierville, in the Province of Quebec and Dominion of Canada, have invented new and useful Improvements in Door-Latches, of which the following is a specification.

This invention relates to securing devices 10 for doors and the like, and has for its object the provision of a very efficient latch by means of which a door may be held closed and the construction of which is such that the door may be opened from either side 15 with the utmost ease.

An important object is the provision of a latch of this character in which the parts are so constructed and arranged as to be well balanced so as to facilitate the operation 20 of the latch, the parts being furthermore well fitting and neatly assembled whereby the minimum effort will be required in actuating the latch, while at the same time the latch will be efficient in operation.

An additional object is the provision of a latch of this character which will be simple and inexpensive in manufacture, and installation, highly efficient in use, durable 30 in service, and a general improvement in the art.

With the above and other objects and advantages in view, the invention consists in details of construction to be hereinafter 35 more fully described and claimed, and illustrated in the accompanying drawing, in which—

Figure 1 is an elevation showing my device upon one side of a door,

Fig. 2 is an elevation looking at the other side of the door,

Fig. 3 is a cross sectional view on the line 3—3 of Fig. 1,

Fig. 4 is a cross sectional view on the line 4—4 of Fig. 1,

Fig. 5 is a cross sectional view on the line 5—5 of Fig. 1, and

Fig. 6 is a horizontal longitudinal sectional view on the line 6—6 of Fig. 1.

Referring more particularly to the drawing, the letter A designates a portion of a door and B designates a portion of the stationary jamb or the like.

In carrying out my invention I provide 55 upon the jamb B a keeper formed as a plate 10 secured upon the jamb by suitable screws

or the like and having a portion of its material stamped out to provide a cup-like saddle 11 having its open edge directed upwardly. Disposed for movement over the 60 face of the door A is a long latch bar 12 which is provided with a counter-balancing weight 13 at one end, which is adapted to have its other end engaged within the keeper saddle 11, which is pivoted intermediate its 65 ends upon a stud or the like 14 extending outwardly from a plate 15 mounted upon the door. At a point somewhat removed from the free edge of the door A I provide a guide bracket in the nature of a plate 16 70 secured upon the door and transversely slit, as shown, to provide tongues 17 within which are engaged the ends of a loop-like guide 18 engaging over and extending beyond the edges of the latch bar 12.

Also mounted upon the latch bar 12 at the 75 guide structure just described, is a handle 19 which has its central portion offset from the door and conveniently shaped for comfortable engagement within the hand of an 80 operator. Within its ends the handle is enlarged, as shown at 20, and is provided with slits or slots 21 for the passage of the latch bar 12, it being noted that the latch bar 12 adjacent one end of the handle is slightly 85 widened, as shown.

Disposed upon the opposite side of the door is a handle 22 which has its central portion offset and curved to be comfortable and which has end portions secured upon the 90 door. One end of the handle member 22 is enlarged into a relatively large plate 23 which is provided with a rectangular opening 24 through which and through a corresponding opening in the door extends a lever 95 25 which has its lower end provided with a thumb engaging portion 26. This thumb engaging portion of this latch lever is disposed at the side of the door provided with the handle 22 and the other end of this lever 100 25 extends through the door and is provided with a hook 27 upon which is engaged a link or the like 28 which has its terminal portion engaging within a suitable hole 29 in the end 30 of the handle 19 disposed adjacent the 105 free edge of the door.

Assuming that an operator approaches a door from its inside, in order to open the door it is merely necessary that he grasp the handle 22 and press upon the thumb 110 member 26, whereupon the latch bar 12 will be swung upon its pivot 14 to disengage its

end from the keeper saddle 11. The operator when approaching the door from the outside merely grasps the handle 19 and swings the latch member upwardly, as will be obvious.

From the foregoing description and a study of the drawing, it will be apparent that I have thus provided an extremely simple latch mechanism which may be very quickly and easily operated and which will be highly efficient in use and not likely to get out of order.

While I have shown and described the preferred embodiment of my invention, it is of course to be understood that I reserve the right to make such changes in the form, construction, and arrangement of parts as will not depart from the spirit of the invention or the scope of the subjoined claim.

Having thus described my invention, I claim:

A door securing device comprising a keeper member secured upon the door jamb and having a saddle portion, a latch bar horizontally disposed and pivotally mounted for movement in a vertical plane upon the

door, one end of said latch bar being adapted for engagement within said keeper saddle, a vertically extending guide bracket secured upon the door and engaging said latch bar for limiting movement thereof, a handle having enlarged end portions slotted for the passage of said latch bar and having its intermediate portion offset to provide a handle spaced from said guide bracket, a handle member secured upon the opposite side of the door and having one end formed as an enlarged plate provided with an opening, the door being also provided with an opening registering with said first named opening, an angular lever pivoted within the opening in said plate and having one end provided with a thumb engaging portion and having its other end extending through both of said openings and terminating in a hook, and a link connected at one end with said hook and connected at its other end with the end of said first named handle adjacent the free edge of the door.

In testimony whereof I affix my signature.

JOHN WESLEY WALLACE.
